DESIGN FOR A CHAIR CART

Louis P. Brantz, Philadelphia, Pa.

Application August 5, 1943, Serial No. 110,844

Term of patent 3½ years

(Cl. D14—3)

To all whom it may concern:

Be it known that I, Louis P. Brantz, a citizen of the United States, residing at Philadelphia, in the county of Philadelphia and State of Pennsylvania, have invented a new, original, and ornamental Design for a Chair Cart, of which the following is a specification, reference being had to the accompanying drawing, forming part thereof.

The figure is a perspective view of a chair cart, showing my new design.

I claim:

The ornamental design for a chair cart, substantially as shown.

LOUIS P. BRANTZ.
